FIG. 1

FIG. 2

FIG. 3

FIG. 4

FIG. 5

FIG. 6

FIG. 1 is a top plan view of a bedding plant tray embodying my new design;

FIG. 2 is a side elevational view as seen from the line 2—2 of FIG. 1;

FIG. 3 is an enlarged view of a corner portion of the tray of FIG. 1;

FIG. 4 is a side elevational view along the line 4—4 of FIG. 3;

FIG. 5 is a sectional view through a portion of the tray along the line 5—5 of FIG. 3; and

FIG. 6 is a sectional view of a portion of the tray along the line 6—6 of FIG. 3.

The tray pattern shown in FIG. 1 continues uniformly throughout the entire extent of the plant tray, from edge to edge.

I claim:

The ornamental design for a bedding plant tray, as shown and described.
